UNITED STATES PATENT OFFICE.

EMERSON G. REED, OF WILKINSBURG, PENNSYLVANIA, ASSIGNOR TO WESTINGHOUSE ELECTRIC AND MANUFACTURING COMPANY, A CORPORATION OF PENNSYLVANIA.

TRANSFORMER.

1,231,648.

Specification of Letters Patent. Patented July 3, 1917.

Application filed November 28, 1913. Serial No. 803,512.

To all whom it may concern:

Be it known that I, Emerson G. Reed, a citizen of the United States, and a resident of Wilkinsburg, in the county of Allegheny and State of Pennsylvania, have invented a new and useful Improvement in Transformers, of which the following is a specification.

My invention relates to alternating current transformers and inclosing casings 10 therefore, and it has for its object to provide a simple and effective means for holding together the plates or laminae of which the core structure is composed, and other means for securing the transformer within the 15 casing.

Many transformers, as at present constructed, comprise concentric primary and secondary coils which are approximately circular or elliptical in transverse section, 20 the coils being embraced, at opposite sides, by a plurality of magnetizable core members arranged in radial planes. The core members are built up of plates or laminae which must be suitably retained in end 25 frames in order that the transformer may be conveniently and expeditiously handled without injuring the coils and without disarranging the elements of the core structure. It is also important to provide a 30 means whereby the transformer, after having been assembled, may be readily and securely positioned in its containing case.

According to my invention, I provide an inclosing tank which is constructed to receive a transformer of the character indicated above and which is provided with means for engaging the end frames of the core structure, whereby the transformer may be securely held in position after the 40 same has been assembled and disposed therein. Furthermore, I provide new and novel end frames in which the core structure of my transformer is seated.

For a better understanding of the nature, the scope, and the characteristic features of my invention, reference may be had to the following description and the accompanying drawing in which Figure 1 is a plan view and Fig. 2 is a view, partially 45 in elevation and partially in section, of a transformer embodying a form of my in-

vention; Figs. 3 and 4 are plan and side views, respectively, of the lower end frame of my transformer; Fig. 5 is a side view, taken at right angles to the view embodied in Fig. 2, of an upper end frame constructed in accordance with my invention, and Fig. 6 is a view of a member to be hereinafter described.

Referring to the drawings, the device disclosed comprises an inclosing casing consisting of a tank 1 and a cover 2, and a transformer comprising a plurality of core members 3, 4, 5 and 6, coils 7, end frames 8 and 9, a high-tension terminal block 10 and a 60 low-tension terminal bracket 11.

The relatively large members 5 and 6 of the core are disposed at right angles to the relatively small members 3 and 4, the amount of magnetizable material or iron 65 composing the members 5 and 6 being about 75 per cent. by weight of the iron in the entire core structure. As shown, each of the members of the core is built up of laminations in the usual manner. After 70 the core members have been assembled, they are positioned in their respective seats which are formed in the end frame 8, the aligned core members 5 and 6 being disposed in a lower channel formed in an arm 12 and, 75 similarly, the members 3 and 4 being disposed in a channel formed in an upper arm 13 which extends at right angles to that of the channel 12. In order that the core 80 may occupy a minimum space within the coils 7, the core members 5 and 6 abut against each other, while the core members 3 and 4 are located with their adjacent edges abutting the sides of the members 5 and 6, 85 with lock irons 14 positioned intermediate the engaging surfaces thereof.

The lock irons 14, rectangular in form and substantial in construction, are provided, at their upper and lower portions, with punched holes 15 through which bolts 90 project to secure the core structure to the lower and upper end frames 8 and 9, as shown in Fig. 2.

Referring to Figs. 3 and 4, the lower end frame 8 is cast in the form of a square cross 100 with the divided arm 13 providing a channel which crosses a channel in the arm 12, at

a higher elevation. The core members 5 and 6 are positioned in the channel of the arm 12 and the core members 3 and 4 are disposed in the channel of the arm 13, as above mentioned. The sides of the arm 12 are centrally apertured with openings 17 which are aligned with the openings 15 in the lower portion of the lock irons 14, when said lock irons are placed in position. The bolt 16 secures the lock irons to the frame 8 but does not engage the laminations of which the core members 5 and 6 are composed, because of the open space provided therebetween, as a result of the corners of the laminations having been removed.

The end frame 8 is provided with a tapered opening 18 which engages a central projection 19 on the floor of the tank 1. By this means, the transformer is maintained in a fixed position within the tank, and disarrangement of the elements of the core structure during the handling of the transformer is precluded. Flanges 20, formed on the arm 12, constitute feet by means of which the transformer is firmly positioned upon the engaging surface of the tank bottom, as shown in Fig. 2. Inasmuch as the weight of the members 5 and 6, which constitutes 75 per cent. of that of the core structure, is centrally supported upon the arm 12, there is no tendency to overbalance the core structure by reason of the laterally projecting members 3 and 4 when the transformer is placed upon a substantially level surface, such as the bottom of the tank.

The upper end frame 9 is provided with a main arm 21 in which is formed a channel to receive the core members 5 and 6 and with a divided arm 22 in which is formed a channel to receive the core members 3 and 4. As explained relative to the lower end frame 8, the core members are positioned in their respective channels, and a bolt 16, projecting through openings 23 in the end frame 9 and the openings 15 in the upper portion of the lock irons 14, insures rigidity to the upper portion of the core structure. In order to maintain the transformer centrally within the tank 1, bars 24 extend in radial planes from the end frame 9 to the corners of the tank 1. One end of each of the Z-shaped tie bars 24 is bolted to a plate 25 which is integral with the end frame 9, and the other end is bolted to a lug 26 which is cast in the tank 1, substantially as shown.

The upper end frame 9 is provided with upwardly extending supports 24^a to the top of one of which the high-tension terminal block 10 is secured, and to the top of the other of which the low-tension terminal bracket 11 is secured. Conductors 27 and 28, leading from the terminal member 10 and 11, respectively, project through bushings 29 provided in the walls of the tank, thereby

affording means for connecting the high-tension and low-tension coils of the transformer to the external apparatus that may be associated therewith.

The web member 30, which extends intermediate to the supports 24^a, is provided with an opening which may be engaged by a crane hook in lifting the transformer from the casing. Thus engaged, the lock irons 14 sustain the stresses and strains by reason of the weight of the transformer being imposed thereupon, and, therefore, the transformer may be handled without injury to the coils and without warping the core structure or disarranging its elements.

Inasmuch as various structural modifications may be effected in the device illustrated without departing from the spirit of my invention, I desire that only such limitations shall be imposed as are indicated in the appended claims.

I claim as my invention:

1. A transformer comprising a tubular winding, a plurality of core sections embracing the winding and disposed in substantially radial planes, said core members being composed of relatively long and relatively short units, the relatively long units being composed of a preponderance of the required magnetizable material, end frames therefor each constituting a plurality of arms which are provided with channels formed to receive the outer ends of the corresponding magnetizable core members, and lock irons disposed intermediate the adjacent relatively long core members and extending between the upper and lower end frames.

2. The combination, in a transformer having approximately cylindrical primary and secondary coils, of a plurality of laminated core members embracing the coils, end frames providing seats for the core members and maintaining the relative positions thereof, lock irons interposed between the respective core members and extending intermediate the end frames, and bolts engaging only the said lock irons and end frames.

3. The combination, in a transformer having approximately cylindrical coils, and relatively large and relatively small core members embracing the coils, of end frames for the core members providing seats whereby the relatively large core members may abut against one another, lock irons laterally disposed to the adjacent sides of the relatively large core members, and means firmly securing the said lock irons to the end frames.

4. The combination with an inclosing casing, of a transformer comprising a tubular winding, a plurality of core members embracing the winding and disposed in substantially radial planes, top and bottom

end frames for the core members, said end frames constituting a plurality of integrally formed arms which correspond to said core members and being provided with channels 5 to receive the outer ends thereof, and the upper end frame being provided with accessible lifting means, and means independent of said core members for locking said end frames to each other, whereby the active por-

tion of the transformer may be lifted from 10 said containing casing.

In testimony whereof, I have hereunto subscribed my name this 24th day of Nov. 1913.

EMERSON G. REED.
